UNITED STATES PATENT OFFICE

WILLIAM H. SAUVAGE, OF NEW YORK, N. Y., ASSIGNOR, BY MESNE ASSIGNMENTS, TO
GOULD COUPLER COMPANY, OF NEW YORK, N. Y.

SLACK ADJUSTER

Application filed February 9, 1925. Serial No. 7,954.

This invention relates to improvements in slack adjusters, and more particularly to automatic slack adjusters particularly adapted for use on the trucks of railway cars, although it is of course to be understood that certain features of the invention are applicable to other parts of the brake riggings.

One of the objects of the present invention is to provide an improved slack adjuster of the above general character having relatively few parts, which may be inexpensively manufactured, assembled, and installed.

A further object is to provide a slack adjuster which may be applied to the truck 10 brake rigging without material alteration of the parts now in standard use.

A further object is to provide an improved 20 brake adjusting device which will be more reliable than those now in use and will accurately take up the slack at each complete operation of the brakes, thereby to provide uniform piston travel or travel of the brake actuating means. Other objects will be in part obvious or in part pointed out herein- 25 after.

In the accompanying drawings in which like reference characters refer to similar parts throughout the several views of the drawing,

30 Figure 1 is an elevational view of such parts of the truck brake rigging and slack adjuster applied thereto as is necessary to understand the invention;

35 Figure 2 is an enlarged detail view of a slack adjuster, certain parts being shown in section for convenience.

Referring now to the drawings in detail and more particularly to Figure 1, 5 indicates the usual truck bolster provided at one side with an adjustable hanger 6 supporting the upper end of a dead lever 7. At the opposite side of the bolster, there is the live lever 8 having a brake actuating pull rod 10 adapted to be connected to the foundation brake rigging or hand actuated device according to the type of actuating means utilized. Both of the levers 7 and 8 are provided with the usual brake beam structures, which 50 are, of course, provided with brake shoes for

coacting with the peripheries of the wheels in the well known manner.

The lower ends of these levers, instead of being connected with the usual rigid push rod, have supported thereby the slack adjuster mechanism which is shown more clearly in Figure 2. This includes a rod-like member 14 and a tubular member 15, the latter being enlarged at one end to provide a housing 16 containing a plurality of dogs 17 normally held in actuated position in the usual manner, as by means of a coil spring 18 reacting between one of the dogs and the end wall of the housing 16.

This housing is provided with two projecting ears 20 and 21 having openings therein through which a takeup or adjusting rod 22 passes. The end of this rod 22 curves upwardly and is provided with an eye 23 coacting with the element supporting the fulcrum 7 (not shown) of the brake beam 11.

Between these ears 20 and 21 there is located a friction take-up device which includes a member 24 having a beveled surface 25 adapted to coact with the frustoconical end of a friction device 26, preferably formed of two semi-cylindrical members, both ends of which are tapered in the manner shown. The tapered portion 27 is engaged by a beveled ring 28 normally urged into engagement therewith by means of a coil spring 30 reacting between a shoulder 31 of the ring 28 and the end wall 32 of the containing member 24. Thus, the friction device 26 is urged constantly into engagement with the rod 22. 85

It will also be noted that this containing member 24 is slightly shorter than the distance between the ears 20 and 21, thereby to provide a certain amount of lost motion which will at all times insure brake shoe clearance.

As shown in Figure 2 the dogs 17 may be released by inserting a bar 33 in front of a pin 34 on the ring member 28 extending through an elongated slot in the container 24 95 and the dogs 17. Thus, when this bar is moved towards the left it will force the member 28 in that direction to compress the spring 30 and relieve the tension upon the friction device 26. It will also straighten 100

out the dogs 17 to a position normal to the rod 14 against the action of the spring 18, thereby permitting the rod 14 to be moved freely in either direction with respect to the dogs 17. Likewise the rod 22 is rendered fully movable, thus restoring the parts to normal position or original position, as is necessary when replacing worn brake shoes, for example.

10 The operation of the device is substantially as follows: When the brakes are actuated, the upper end of the live lever 8 moves toward the left, acting through the bottom rod to move the dead lever toward the right, thus 15 applying the brakes. If any excess travel occurs exceeding that provided for between the ear 20 and the containing member 24, the rod 22 will then move freely through the friction device 26 to an amount exactly equal 20 to this excess travel. Such movement will cause a relative change in the fulcrum point 23. On release of the brakes the live lever returns to normal position, but the fulcrum point 23 is held in its newly adjusted position 25 by reason of the friction devices 26, which cause a further relative travel of the lower end of the live lever 8, thereby pulling it towards the left with respect to the holding dogs 17. Thus, at the completion of each 30 cycle of operation, all of the excess travel is fully and completely taken up and permanently held by the adjuster.

As above explained, when it is desired to replace the brake shoes, the rod 33 is inserted 35 to move the dogs 17 over against the stop 35, which simultaneously relieves the pressure upon the friction devices 26 and permits both rods 14 and 22 to be returned to normal position.

40 It is thus seen that the present invention provides a simple and practical slack adjuster mechanism well adapted to accomplish among others all the advantages and objects herein set forth.

45 Without further analysis, the foregoing will so fully reveal the gist of this invention that others can by applying current knowledge readily adapt it for various applications without embodying certain features 50 that, from the standpoint of the prior art, fairly constitute essential characters of the generic or specific aspects of this invention and, therefore, such adaptations should and are intended to be comprehended within the 55 meaning and range of equivalency of the following claims.

I claim as my invention:

1. In a device of the character described, in combination, an adjusting rod, a two-part 60 friction member embracing said rod, and a beveled ring receiving an end of said member and enclosing spring means for holding said friction device in yielding engagement with said rod.

65 2. In a device of the character described,

in combination, an adjusting rod, a two-part friction member embracing said rod, and a spring device holding said friction device in yielding engagement with said rod, said spring device and friction device being provided with coacting beveled surfaces.

70 3. In a device of the character described, in combination, a two-part telescopic push rod, permanent take-up and holding means associated therewith, supports projecting 75 from one of the parts of said rod on either side of said permanent take-up and holding means, an adjusting rod passing through said supports, and temporary take-up and holding means associated with said rod, said 80 last means having a total length of less than the distance between said supports, whereby brake shoe clearance is insured.

4. In a device of the character described, in combination, supports, and adjusting rod 85 passing through said supports, and take-up and holding means associated with said rod, said last means having a total length of less than the distance between said extending supports, said temporary take-up means including a container, a pair of members embracing said rod and having a wedging engagement with said container, and a yielding device coacting with one end of said friction device and having a wedging en- 90 gagement therewith.

95 5. In a device of the character described, in combination, a two-part telescopic push rod, permanent take-up and holding means associated therewith, supports extending 100 from one of the parts of said rod, an adjusting rod passing through said supports, temporary take-up and holding means associated with said rod, said last means having a total length of less than the distance between said supports, whereby brake shoe clearance is insured, said temporary take-up means including a container, a yielding device coacting with one end of said friction device and having a wedging engagement 105 therewith, and means associated with said container adapted to be engaged by an elongated tool thereby to simultaneously release both the temporary and permanent take-up and holding devices.

110 Signed at New York city this 8th day of January, 1925.

WILLIAM H. SAUVAGE.
